UNITED STATES PATENT OFFICE

MERTON W. HOWARD, OF LYNN, MASSACHUSETTS, ASSIGNOR TO POPE MACHINERY CORPORATION, OF HAVERHILL, MASSACHUSETTS, A CORPORATION OF MASSACHUSETTS

HEEL CONCAVING MACHINE

Application filed December 1, 1931. Serial No. 578,251.

This invention relates to machines for concaving the seat of wood heels and, particularly, to machines of the general type described in a co-pending application of 5 Walter C. Brooks and John W. Staples, Serial No. 379,918, filed October 7, 1929. In general, the machine described in the above mentioned application comprises a stationary support having a slot through 10 which projects a rotating cutter. A heel guide is carried over the support and extends over the slot adjacent the edge of the cutter to engage the edge of a seat of a heel while it is being moved over the cutter. A 15 heavy arm is pivotally mounted upon the machine and is provided with two spaced surfaces substantially parallel to the support between which slides a cam or pattern having a portion which corresponds substan- 20 tially with the edge contour formed by the back and sides of the heel seat. This cam carries a clamp for holding a wood heel. The cam is rotated while being guided to cause the heel to move through a predeter- 25 mined path first along a portion of the path in engagement with the cutter and then along the remaining portion of the path to its initial position. A resilient pressure acts upon the heavy pivoted arm to maintain the 30 edge of the seat of the heel in engagement with the heel guide while the heel is engaging the cutter. As the heel is returned toward its initial position, the heel is ejected and the cam is stopped so that another heel 35 may be placed in the clamp. After the clamp has been stopped and another heel placed in the clamp the foot pedal is actuated to operate a clutch and start the ma- 40 chine through another cycle. 45 Heretofore it has been common practice in operating concaving machines to stop the heel clamping mechanism after each heel has been concaved to permit the removal of the heel, and more particularly, to allow the operator to insert another heel. In the ma- 50 chine described in the above mentioned co-pending application the ejection of the concaved heel is accomplished automatically while the clamp is still in motion but the clamp comes to a stop to permit re-loading

and the machine must be started again by the operator to concave the next heel.

The starting of the machine, usually by a foot pedal, requires a definite effort which in view of the large number of heels these 55 machines handle in a day adds up to a considerable expenditure of energy, as well as requiring close attention to the timing of the machine in order to obtain maximum production. It is well established that close 60 attention increases fatigue. The time lost by stopping and starting the machine at the end and beginning of each cycle of operation amounts to about 25 percent of the time re- 65 quired to complete each cycle, varying ac- cording to the skill of the operator.

In accordance with the present invention, the heel holding and moving mechanism is not stopped at the end of each cycle to permit ejection of the heel or the insertion of 70 another heel. On the contrary, the heel holding and moving mechanism is moved continuously, first, through a range wherein the heel is concaved, then through a range wherein the heel is ejected, and, thereafter, 75 through a loading range wherein another heel is inserted in the heel holding mechanism. A loading mechanism is provided which operates automatically to move a heel into the heel holding mechanism as the lat- 80 ter is moving through the loading range and then returns to its inoperative initial position well away from the cutter or other moving parts of the machine so that the operator may insert a heel therein. 85

The present invention eliminates the time lost due to starting and stopping the machine thereby increasing production by about 33 1/3 percent. This saving, in practice, is increased further due to the lessened 90 fatigue of the operator. Inasmuch as the loading mechanism of the invention operates to insert a heel in the heel holding mechanism and returns to its initial position at a point well away from the cutter or other 95 moving parts of the machine in a time interval which is about 25 percent of the time required for the heel holding mechanism to move through a complete cycle, the operator has about 75 percent of the time required for 100

a complete cycle in which to insert another heel in the heel loading mechanism. This greatly increases the safety factor and allows the operator an abundance of time in which to insert a heel in the loading mechanism.

It is well understood that starting and stopping any machine thousands of times daily greatly increases the wear and tear. 10 With the benefit of invention the concaving machine runs continuously at a uniform speed, the mechanical loader being timed to insert the new heel into the clamp immediately after the concaved heel has been ejected and while the clamp is moving at full speed toward the cutter.

The invention will be more clearly understood from the following description in conjunction with the accompanying drawings: 20 in which,

Fig. 1 is a fragmentary elevational view, partly in section, of a machine embodying the invention;

Figs. 2 and 3 are sectional views taken 25 upon the lines 2—2 and 3—3 respectively of Fig. 1;

Fig. 4 is a fragmentary detail sectional view of a portion of the machine; and

Fig. 5 is a view similar to Fig. 2 showing 30 the parts in a different position.

Before explaining in detail the present invention, it is to be understood that the invention is not limited in its application to the details of construction and arrangement 35 of parts illustrated in the accompanying drawings, since the invention is capable of other embodiments and of being practised or carried out in various ways. Also it is to be understood that the phraseology or 40 terminology employed herein is for the purpose of description and not of limitation, and it is not intended to limit the invention beyond the terms of the several claims hereto appended as considered in view of the 45 prior art and the requirements thereof.

The construction of the machine illustrated in the accompanying drawings is similar to that of the machine illustrated in the above mentioned co-pending application and 50 comprises a frame 10 carrying a stationary support 11. A cutter 12 extends upwardly through a slot 14 in the support 11 and is carried by a shaft 15 mounted for rotation in suitable bearings (not shown). A heel guide 16 is adjustably mounted in any suitable manner upon the support 11 and extends over the slot 14 adjacent the edge of 55 the cutter 15. The shaft 15 is rotated from any suitable source of power (not shown) 60 to rotate the cutter 12.

A heavy arm 20 carried upon the frame 10 is provided at its free end with spaced shelves 21 and 22 substantially parallel to the support 11 and between which a cam or pattern 23 is slidably mounted. Prefer-

ably, the arm 20 is pivotally mounted on the frame and is urged towards a stop by a heavy spring as described in the above mentioned co-pending application. The cam 23 is formed with a body portion 25 having a continuous wall 26 extending upwardly from the edge thereof. Teeth 27 are provided near the bottom of the outer surface of the wall 26 and are adapted to engage a pinion 29 carried by a shaft 30 rotatably mounted in suitable bearings upon the arm 20. Power is supplied from any suitable source to rotate the pinion 29. The upper edge of the pinion 29 is provided with a blank portion 31 adapted to engage the outer surface of the wall 26 above the teeth 27. A guide roll 32 is rotatably mounted in the arm 20 to engage the upper outer surface of the wall 26 above the teeth 27. The cam 23 is held in engagement with the pinion 29 and the guide roll 32 by a roll 33 engaging the inner surface of the wall 26 and pivotally mounted near the end of the lever 34. The lever 34 is pivotally mounted at an intermediate point upon the arm 20 and is connected at its other end to one end of a spring 35, the other end of which is secured to a bolt (not shown) adjustably mounted upon the arm 20.

A member 40 is fixed to the lower end of a stud 41 depending from the body portion 25 of the cam 23 through a slot 44 in the shelf 22. The member 40 is provided with a bevelled tongue 45 adapted to be received in a similarly shaped guideway in a slide 46. A bevelled tongue 47 depends from the slide 46 and is adapted to be received in a similarly shaped guideway carried by a slide 48. The bevelled tongues 45 and 47 are angularly disposed so that the slides 46 and 48 may be adjusted, preferably, along perpendicular paths. Each of the slides 46 and 48 is held in any desired adjusted position, as by a set screw 49.

Spaced rods 50 are suitably secured in ears 51 extending laterally from opposite sides of the slide 48 and extending downwardly therefrom toward the support 11. A bracket 52 extends between the rods 50 and is suitably secured thereto. A heel gauge 53 is suitably mounted for adjustment in the bracket 52. A slide 55 is slidably mounted in suitable guideways 56 in the gauge 53 and its forward and rearward movement is limited by stops (not shown). 120 A roll 58 is pivotally mounted at the rear end of the slide 55. The sides of the slide 55 are provided with high and low cam surfaces 59 and 60 adjacent the roll 58 and are adapted to be engaged by rolls 61 pivotally mounted upon one end of levers 62 pivotally carried by the rods 50. A heel engaging clamp 64 is adjustably mounted on the other end of each of the levers 62. A rod 66 is slidably mounted in each of a pair of spaced 125 130

bushings 67 pivotally mounted upon the bracket 52. One end of each of the rods 66 is provided with a bearing 68 pivotally engaging a pin 69 on the slide 55. A spring 70 surrounds each of the rods 66 with one end engaging the bushing 67 and its other end engaging the bearing 68. A pair of springs 72 connect the levers 62 and the bushings 67. A roll 73 is pivotally mounted on a bracket 74 extending between and suitably secured upon the rods 50.

An arm 75 is fixed upon a shaft 76 carried by a bracket 77 extending laterally from the arm 20. The arm 75 is fixed in adjusted position upon the bracket 77 by a nut 78 threaded upon the upper end of the shaft 76 and engaging the bracket. An arm 80 is pivotally mounted at an intermediate point upon the shaft 76 and is provided with an abutment 81 adapted to engage a stop 82 upon the arm 75. The abutment 81 normally is held in engagement with the stop 82 by a spring 83, one end of which is connected at one end of the arm 80 and the other end of which is connected to a screw (not shown) adjustably mounted in the end of the arm 75. A projection 84 extends from the lower side of the other end of the arm 80 and is positioned in the plane of movement of the roll 58 carried by the slide 55 and is adapted to swing beneath the roll 73.

A bracket 85 is suitably secured to the slide 48, as by bolts 86, and carries a roll 87. A slide 88 is slidably mounted in guideways 89 suitably secured upon the support 11, as by screws 90. A screw 91 is swivelled in bearing 92 carried by the support 11 and is adapted to engage a lug 93 fixed upon the slide 88. The slide 88 is fixed in its adjusted position by a bolt 94 passing through a slot 95 in the support 11 and engaging the slide 88. An actuating arm in the form of a bell crank 96 is provided with a hub 97 which is pivotally mounted upon a bolt 98 carried by the slide 88. One arm of the bell crank 96 extends into the path of the roll 87. A lever 99 is provided with a hub 100 which is pivotally mounted upon a bolt 101 carried by the slide 88. The other end of the bell crank 96 is provided with a fork 102 which is pivotally connected to trunnions 103 fixed in an enlarged portion of a rod 104. One end of the lever 99 is provided with a fork 105 which is pivotally connected to trunnions 106 carried by a sleeve 107 in which the rod 104 is slidably mounted. A spring 108 surrounds the rod 104 with one end engaging the enlarged portion thereof and its other end engaging one end of the sleeve 107. A sleeve 109 surrounds rod 104 with its inner end engaging the other end of the sleeve 107 and its outer end engaging a nut 110 threaded upon the free end of the rod 104. The lever 99 normally is held in the position shown in Fig. 2 against a suitable

cushioning device by a spring 111 surrounding the hub 100 and with one end secured to the lever 99 and its other end secured to the head of the bolt 101.

The cushioning device includes a plunger 112 slidably mounted within a guide 113, such as a cylinder having one end closed, forming part of a bracket 114 which is suitably secured upon the support 11, as by screws 115. The plunger 112 is normally urged toward the lever 99 by a spring 116 surrounding the reduced end portion of the plunger and engaging the closed end 117 of the guide. The other end of the plunger is provided with a socket in which a block 120 of rubber or the like is secured. The closed end 117 of the guide 113 is provided with an air passage 121 controlled by a needle valve 122. A stop 400 is suitably fixed on the support 11 and serves to limit the inward movement of the plunger 112 when the latter is not in engagement with the arm 99.

A rod 125 having a V-shaped end 126 is adjustably mounted in an opening in the free end of the lever 99 and is secured in adjusted position therein, as by a bolt 127. A block 130 is adjustably mounted upon the rod 125 and for this purpose is provided with an opening adapted to receive the rod 125. The block 130 is held in adjusted position upon the rod 125, as by a set screw 131. The block 130 is provided with a guideway 132 adapted to receive a slide 133 which is adjustably secured therein by a bolt 134 passing through a slot 135 in the slide 133 and engaging the block 130. A spring leaf 136 is suitably secured at one end to the upper end of the slide 133 and extends therefrom above the rod 125 so as to engage the bottom of a heel W positioned in the V-shaped end 126 of the rod 125.

The operator places a heel W in the V-shaped end 126 and beneath the spring 136 as shown in Figs. 2 and 4. Power is then supplied from any suitable source to rotate the cutter 12 and the pinion 29 continuously causing the cam 23 to be rotated between the shelves 21 and 22. The rotation of the cam 23 causes the roll 87 carried by the bracket 85 to engage the free end of the bell crank 96 to turn the same and cause it to exert a resilient force tending to turn the lever 99. This movement of the lever 99 from its initial position as shown in Fig. 2, moves the heel W into engagement with the slide 55 to move the latter rearwardly. As the slide 55 moves rearwardly the rolls 61 carried by the arms 62 move from the low cam surfaces 59 to the high cam surfaces 60 and cause the clamps 64 to move into engagement with the heel W and hold the same against the support 11.

When the roll 87 has moved out of engagement with the bell crank 96, the spring 111 acts to return the lever 99 to its initial

position in engagement with the plunger 112 which serves to prevent rebound of the lever. Further movement of the cam 23 causes the heel holding clamp to move 5 through the heel cutting range to bring the heel W into engagement with the cutter 12 to produce a concaving cut along the sides and back of the heel seat and to thereafter move the heel holding clamp along a different path through the heel ejecting range and then through the heel loading range. As the heel holding clamp approaches the heel loading position the roll 73 engages the arm 80 to swing the latter rearwardly against the action of the spring 82. When the roll 73 rides off the end of the arm 80, the arm 80 is swung forwardly by the action of the spring 82 to bring the projection 84 into engagement with the roll 58 to move the slide 55 forwardly. As the slide 55 moves forwardly the rolls 61 move from the high cam surfaces 60 to the low cam surfaces 59 to permit the springs 72 to separate the clamps 64 and permit the slide 55 to eject the heel. 25 Immediately thereafter the roll 87 again comes in engagement with the bell crank 96 to move the same and to cause another heel, which the operator has placed between the spring 136 and the V-shaped end 126, to be moved into the open clamp while the cam 23 carrying the same is being moved along its predetermined path through the loading range.

I claim:

35 1. A machine for concaving heels having, in combination, a cutter, means for holding a heel including a heel clamp, means for moving the heel holding means continuously through a predetermined path which 40 path includes a heel cutting range, a heel ejecting range and a heel loading range, means operative to open said clamp and eject the heel while the heel holding means is moving through the ejecting range, and 45 means to move a heel into said open clamp, and close the clamp while the heel holding means is moving through the heel loading range.

2. A machine for concaving heels having, 50 in combination, a cutter, means for holding a heel including a heel clamp, means for moving the heel holding means continuously through a predetermined path which path includes a heel cutting range, a heel 55 ejecting range and a heel loading range, means operative to open said clamp and eject the heel while the heel holding means is moving through the ejecting range, and means to move a heel into said open clamp 60 and close the clamp while the heel holding means is moving through the heel loading range, including an actuating arm extending into the path of movement of said heel holding means.

65 3. A machine for concaving heels hav-

ing, in combination, a cutter, means for holding a heel including a heel clamp, means for moving the heel holding means continuously through a predetermined path which path includes a heel cutting range, a heel ejecting range and a heel loading range, mechanism adapted to open said clamp and eject a heel and to close said clamp, means operative to actuate said mechanism to open said clamp and eject a 70 heel while the heel holding means is moving through the ejecting range, a movable member for moving a heel into said open clamp and to actuate said mechanism to close the clamp, and means for actuating said member as the heel holding means is moving through its loading range. 75

4. A machine for concaving heels having, in combination, a cutter, means for holding a heel including a heel clamp, means for moving the heel holding means continuously through a predetermined path which path includes a heel cutting range, a heel ejecting range and a heel loading range, mechanism adapted to open said clamp and eject a heel and to close said clamp, means operative to actuate said mechanism, to open said clamp and eject a heel while the heel holding means is moving through the ejecting range, a movable member for moving a heel into said open clamp and to actuate said mechanism to close the clamp, means for actuating said member as the heel holding means is moving through its loading range, means for returning said member to its initial position, and means for stopping said member including a resilient cushion adapted to engage the same as it approaches its initial position. 90

5. A machine for concaving heels having, in combination, a cutter, means for holding a heel including a heel clamp, means for moving the heel holding means continuously through a predetermined path which path includes a heel cutting range, a heel ejecting range and a heel loading range, mechanism adapted to open said clamp and eject a heel and to close said clamp, means operative to actuate said mechanism to open said clamp and eject a heel while the heel holding means is moving through the ejecting range, a movable member for moving a heel into said open clamp and to actuate said mechanism to close the clamp, means for moving said member toward its initial position, means adapted to engage said member as it approaches its initial position and effective to reduce the speed of movement of said member so as to bring it to a complete stop at its initial position without rebound. 110

6. A machine for concaving heels having, in combination, a cutter, means for holding a heel including a heel clamp, means for moving the heel holding means continuously 115

- through a predetermined path which path includes a heel cutting range, a heel ejecting range and a heel loading range, mechanism adapted to open said clamp and eject a heel 5 and to close said clamp, means operative to actuate said mechanism to open said clamp and eject a heel while the heel holding means is moving through the ejecting range, a movable member for moving a heel into 10 said open clamp and to actuate said mechanism to close the clamp, an actuating member extending into the path of movement of said heel holding means, means for connecting said members, means for returning said 15 members to their initial positions, and a cushion adapted to engage one of said members as said movable member approaches its initial position.
7. A machine for concaving heels having, 20 in combination, a cutter, means for holding a heel including a heel clamp, means for moving the heel holding means continuously through a predetermined path which path includes a heel cutting range, a heel ejecting 25 range and a heel loading range, mechanism adapted to open said clamp and eject a heel and to close said clamp, means operative to actuate said mechanism to open said clamp and eject the heel while the heel holding 30 means is moving through the ejecting range, and adjustable means for moving a heel into said open clamp and to actuate said mechanism to close the clamp while the heel holding means is moving through the heel loading 35 range.
8. A machine for concaving heels having, in combination, a cutter, means for holding a heel including a heel clamp, means for moving the heel holding means continuously 40 through a predetermined path which path includes a heel cutting range, a heel ejecting range and a heel loading range, a support, a slide movable to engage the heel, connections between the slide and clamp operative 45 upon movement of the slide in one direction to clamp the heel and upon movement of the slide in the opposite direction to open the clamp to permit ejection of the heel, means operative as said holding means moves 50 through its ejecting range to move said slide to cause it to open the clamp and eject the heel, and means operative as the holding means moves through its loading range to move a heel into said open clamp to move 55 said slide and cause said clamp to engage the heel.
9. A machine for concaving heels having, in combination, a cutter, means for holding a heel including a heel clamp, means for 60 moving the heel holding means continuously through a predetermined path which path includes a heel cutting range, a heel ejecting range and a heel loading range, mechanism adapted to open said clamp and eject a heel 65 and to close said clamp, means operative to actuate said mechanism to open said clamp and eject the heel while the heel holding means is moving through the ejecting range, and means to move a heel into said open clamp and to actuate said mechanism 70 to close the clamp while the heel holding means is moving through the heel loading range, including a support, a slide adjustably mounted on the support, a pair of arms each pivotally mounted at an intermediate point upon said slide, one end of one of said arms extending into the path of movement of said holding means, one end of the other arm being arranged to move a heel into said open clamp, and resilient means operatively 75 connecting the other ends of said arms.
10. A machine for concaving heels having, in combination, a cutter, means for holding a heel including a heel clamp, means for moving the heel holding means continuously through a predetermined path which path includes a heel cutting range, a heel ejecting range and a heel loading range, mechanism adapted to open said clamp and eject a heel and to close said clamp, means operative to actuate said mechanism to open 80 said clamp and eject the heel while the heel holding means is moving through the ejecting range, and means to move a heel into said open clamp and to actuate said mechanism to close the clamp while the heel holding means is moving through the heel loading range, including a support, a slide adjustably mounted on the support, a pair of arms each pivotally mounted at an intermediate point upon said slide, one end of one of said arms extending into the path of movement of said holding means, one end of the other arm being arranged to move a heel into said open clamp, and resilient means operatively 85 connecting the other ends of said arms.
11. A machine for concaving heels having, in combination, a cutter, means for holding a heel including a heel clamp, means for moving the heel holding means continuously through a predetermined path which path includes a heel cutting range, a heel ejecting range and a heel loading range, mechanism adapted to open said clamp and eject a heel and to close said clamp, means operative to actuate said mechanism to open 90 said clamp and eject the heel while the heel holding means is moving through the ejecting range, and means to move a heel into said open clamp and to actuate said mechanism to close the clamp while the heel holding means is moving through the heel loading range, including a support, a slide adjustably mounted on the support, a pair of arms each pivotally mounted at an intermediate point upon said slide, one end of one of said arms extending into the path of movement of said holding means, one end of the other arm being arranged to move a heel into said open clamp, and resilient means operatively 95 connecting the other ends of said arms.
12. A machine for concaving heels having, in combination, a cutter, means for holding a heel including a heel clamp, means for moving the heel holding means continuously through a predetermined path which path includes a heel cutting range, a heel ejecting range and a heel loading range, mechanism adapted to open said clamp and eject a heel and to close said clamp, means operative to actuate said mechanism to open 100 said clamp and eject the heel while the heel holding means is moving through the ejecting range, and means to move a heel into said open clamp and to actuate said mechanism to close the clamp while the heel holding means is moving through the heel loading range, including a support, a slide adjustably mounted on the support, a pair of arms each pivotally mounted at an intermediate point upon said slide, one end of one of said arms extending into the path of movement of said holding means, one end of the other arm being arranged to move a heel into said open clamp, and resilient means operatively 105 connecting the other ends of said arms, means for returning said arms to their initial positions, and means effective during a short final portion of the range of movement of the heel moving arm to offer an increasing resistance to the movement thereof as it approaches its initial position and stop the same at its initial position without rebound.
